UNITED STATES PATENT OFFICE.

WILLIAM A. HELL, OF DAVENPORT, IOWA.

SAFETY CRANK ATTACHMENT FOR INTERNAL-COMBUSTION ENGINES.

1,186,187.

Specification of Letters Patent.

Patented June 6, 1916.

Application filed July 19, 1915. Serial No. 40,730.

To all whom it may concern:

Be it known that I, WILLIAM A. HELL, a citizen of the United States, residing at Davenport, in the county of Scott and State of Iowa, have invented certain new and useful Improvements in Safety Crank Attachments for Internal-Combustion Engines; and I do declare the following to be a full, clear, and exact description of the invention, such as will enable others skilled in the art to which it appertains to make and use the same.

This invention relates to new and useful improvements in engine attachments, and more particularly to cranking attachments for internal combustion engines.

The object of the invention is to provide an attachment for a starting crank such as is used on internal combustion engines, which holds the same when in inoperative position, and also prevents accidents resulting from backfiring of the engine which causes the crank to revolve rearwardly, by stopping the impetus given thereto immediately.

A further object of the invention is to provide a device which is simple and durable in construction, inexpensive to manufacture and one which will be very efficient in operation.

With these and numerous other objects in view, my invention consists of the novel features of construction, combination and arrangement of parts which will be herein referred to and more particularly pointed out in the specification and claims.

In the accompanying drawings: Figure 1 is an elevation of my improved crank holder attached to the front of an automobile; Fig. 2 is a vertical section of the same taken on the line 2—2 of Fig. 1; Fig. 3 is a perspective view of this device; Fig. 4 is a perspective view similar to Fig. 3 only taken from the other side.

In describing my invention, I shall refer to the accompanying drawings in which similar reference characters designate corresponding parts throughout the several views and in which the letter S indicates the supporting structure of this device which is shown in the drawings as comprising the front portion of a chassis of an automobile, and secured to this supporting structure S is a crank C which is mounted to revolve

and reciprocate thereon as is usual in cranks of this character. This crank is normally held outwardly in inoperative engagement, but upon being forced inwardly or rearwardly, the rear end of the same will engage the shaft, of the engine that propels the vehicle. This structure involved is of the ordinary type used, and is too well known to make it necessary for the same to be further illustrated. This structure forms no part of my invention and may be of any desired type used on various makes of automobiles.

Attached to the supporting structure S at 1 is my improved attachment which is designated by the numeral 2. This attachment consists of a vertical portion 3 having an aperture 4 therethrough, said vertical portion being secured to the outer face of the support S at 1, by means of a bolt 5 which projects therethrough and holds the parts together by means of a securing nut 6. The lower extremity of the vertical portion 3 of the strip 2 has a bracing foot 7 which when this strip is in position, projects beneath the bottom of the support S to additionally securely fasten the strip to said support. The strip 2 extends obliquely outward from the upper extremity of the vertical portion 3 as shown at 8, to form a cam and into the path of the crank C when the same revolves, the outer extremity of said projecting portion or cam 8 having formed at its outer end, a laterally outwardly projecting stop 9 for the said crank as will be hereinafter more fully described. Positioned longitudinally on the inner side of the obliquely projecting portion of the said strip is a spring metal latch member 10 which has its lower portion thereof 11 secured to the said strip by fastening members 12, and its upper portion 13 projecting laterally from the said strip in the opposite direction from which the stop 9 of the same projects. This projecting upper portion 13 of the latch member has formed intermediate its ends 100 a curved crank receiving seat 14 which is adapted to hold a portion of the said crank when the same is in inoperative position, between the same and the strip 2 as clearly shown in Fig. 2 of the drawings.

In operation when the crank is in normal position and it is desired to hold the same, it will be positioned between the laterally

projecting end 13 of the latch member 10 and the inner side of the strip 2, in the crank receiving curved portion formed to receive the same as clearly shown in Fig. 2 of the drawings. When in this position, the 5 crank will be out of engagement with the engine shaft and to start said engine, it is necessary to disengage the crank from the above described position and swing the 10 same downwardly and then force it inwardly into engagement with the engine shaft whereby upon movement of revolving the same, a rotary movement will be imparted to the engine shaft to start the 15 engine.

If starting the engine by revolving the 20 crank should cause the engine to backfire, a retrograde movement would be imparted to the said crank and the same would swing in the opposite direction until it would strike the obliquely projecting portion 8 of the strip 2, where, owing to the fact that the 25 said portion of the strip projects forwardly, the crank will be out of engagement with the engine shaft to thereby avoid any further retrograde movement from the said shaft. The crank is brought to a positive stop by means of the lip 9 at the extremity of the 30 obliquely projecting portion of the strip 2 which engages the said crank and its under portion holds the same from any further movement. This lip will stop the movement of the crank and prevent the same from revolving completely around whereby it 35 would be likely to strike the operator and injure him severely, as so often happens upon backfiring of the engine while cranking the machine.

This attachment, owing to its particular 40 structure and arrangement with respect to the support and crank of an automobile, and the performance of the aforesaid function, obviates all danger of backfiring while turning the crank to start the engine. It furthermore provides a simple and efficient 45 means for firmly and securely holding the crank when the same is in inoperative position.

From the foregoing description of the 50 construction of my improved attachment to cranks for automobiles, the manner of applying the same to use and the operation thereof will be readily understood and it will be seen that I have provided a simple, 55 efficient and inexpensive means for carrying out the objects of this invention.

While I have particularly described the 60 elements best adapted to perform the functions set forth, it is obvious that various 65 changes in the minor details of construction, form, or proportion, may be resorted to within the scope of the appended claims without departing from the spirit or sacrificing any of the principles of this invention.

1 claim as my invention:

1. In a device of the character described, the combination with a supporting structure, and a crank mounted to revolve and reciprocate thereon; of a stationary cam 70 having one end fixed to the supporting structure and extending outwardly and upwardly in the path of the crank to reciprocate the same to inoperative position upon its retrograde movement, and an angular projection on the free end of said cam to positively stop the retrograde movement of said crank when moved to inoperative position.

2. In a device of the character described, 80 the combination with a supporting structure, and a crank mounted to revolve and reciprocate thereon; of a stationary cam having one end fixed to the supporting structure and extending outwardly and upwardly therefrom, an angular projection on the free end of said cam, and a latch member on said end of the cam to hold the crank when in inoperative position.

3. In a device of the character described 90 the combination with a supporting structure, and a crank mounted to revolve and reciprocate thereon; of a metal strip secured at one end to said supporting structure and projecting obliquely therefrom in the path 95 of the rotary movement of the crank, a laterally projecting lip at the extremity of the other end of said strip to form a stop for said crank.

4. In a device of the character described 100 the combination with a supporting structure, and a crank mounted to revolve and reciprocate thereon; of a metal strip having a vertical portion at one end secured to the 105 supporting structure, a bracing foot on the lower end of said portion to engage the bottom of said support, said strip projecting obliquely outward from the upper end of the said vertical portion, a laterally projecting lip on the extremity of the obliquely projecting portion of said strip, and a spring 110 latch secured to said obliquely projecting section of the strip to hold the crank when in inoperative position.

5. In a device of the character described 115 the combination with a supporting structure, and a crank mounted to revolve and reciprocate thereon; of a metal strip having a vertical portion at one end secured to the 120 supporting structure, a bracing foot on the lower end of said portion to engage the bottom of said support, said strip projecting obliquely outward from the upper end of the said vertical portion; a laterally projecting lip on the extremity of the obliquely projecting portion of said strip, a longitudinally extending spring metal member having the lower portion thereof secured to the inner side of the said obliquely projecting section and the upper portion pro- 125 130

jecting laterally inwardly therefrom, and my hand in presence of two subscribing
said laterally inwardly projecting portion witnesses.
having formed intermediate its ends a
curved crank receiving face to hold the
5 crank therein when the same is in inoper-
ative position.

In testimony whereof I have hereunto set

WILLIAM A. HELL.
